Paul Lieskar.

UNITED STATES PATENT OFFICE.

PAUL LIESKAR, OF DRONTHEIM, NORWAY.

BRUSH-ATTACHING DEVICE.

No. 866,149.

Specification of Letters Patent.

Patented Sept. 17, 1907.

Application filed October 24, 1906. Serial No. 340,385.

To all whom it may concern:

Be it known that I, PAUL LIESKAR, a subject of the King of Norway, and a resident of Munkegaden 16, Drontheim, Norway, have invented certain new and useful Improvements in Devices for Attaching Brushes and the Like to a Stake, of which the following is a specification.

The present invention relates to a device for attaching brushes, and the like to their stakes.

10 It has been proposed to apply to the bottom end of the stake a holder which grips the brush firmly, and which allows of the same being changed or replaced when desired. My invention relates to an improved form of holder. The lower end of the stake cut off at 15 an oblique angle is made to lie flat on the upper surface of the brush. An arrangement of claws and a spring clamp made from stout wire fixed on the bottom of the stake assure a firm attachment of the brush.

In the drawings two forms of construction are shown. 20 Figure 1 shows a front view of the new device with a brush in position. Fig. 2 shows a side view of the brush holder with a brush in position. Fig. 3 shows a side view of the same form of construction as Fig. 1.

The handle or stake *a* is provided on the front of the 25 lower end with two or more claws *b* which serve to form a firm support for the front end of the brush *c*. *d* is a clamp which is fastened on each side of the handle, and by means of a few windings *e* is made into the form of a spring. The lower end of the stake *a* is advantageously 30 cut off obliquely, so that it makes a good engaging surface *f* for the upper surface of the brush *c*. The brush is therefore firmly secured between the oblique end of the stake, the claws in front *b* and the clamp at the back *d*. The loosening and unfastening of the brush *c* is worked 35 by operating the spring clamp *d*. Since the force of the spring is comparatively great it is desirable to attach a lever contrivance to operate this spring clamp.

In the drawings two forms of construction are shown. In the form of construction shown in Fig. 2 the spring 40 clamp *d* presses on the brush *c*; a bent intermediate part *s* clasps round and under the spring clamp *d*, and the ends are jointed at the sides of the stake to the short arms *r* of the lever *t*, *r*. The lever *t*, *r* is bent round the pin *m* on each side of the stake. The pin *m* forms the 45 fulcrum of the lever. The long arm *t* is bent round at the back of the stake. On raising the long arm *t* of the lever, the short arm forces out the bent part *s*, which thereby raises the spring clamp *d* from the brush. The latter is then free and can be easily taken out.

In the form of construction shown in Figs. 1 and 3 the 50 bent intermediate part *n* clasps round and under the spring clamp *d*, and its ends are attached at the sides of the stake to the short arms *g* of the lever *h*, *g*. The lever *h*, *g* is bent round the pin *m* on each side of the stake. The pin *m* forms the fulcrum of the lever. The long 55 arm *h* of the lever is bent round the front part of the stake and on pulling it outwards from the stake the spring clamp is raised by the intermediate bent part *n*. The brush can then be removed.

The spikes *o* are intended to provide additional security especially against slipping. By means of the screw *p* and washer *q* the claws are secured more firmly on the front part of the stake, and prevented from bending out.

The new device can be applied in all cases in which a 65 brush is used with a handle. With a short shaft and scrubbing brush it is especially suitable for use by butchers and for household purposes. In conjunction with a long stake it is suitable for brooms and brushes for sweeping.

70 What I claim as my invention and desire to secure by Letters Patent is:—

1. In a device for attaching brushes and the like to a stake the combination of a clamp, spiral springs sunk in recesses in the sides of the stake actuating said clamp, 75 claws projecting over the front end of the stake, fixed in position by means of a washer and screw, an oblique surface on the end of the stake, adapted to rest firmly on the top of the brush, the brush being fixed between the clamp, claws, and oblique surface, means to prevent the brush from slipping, and means to draw back the clamp, substantially as set forth.

2. In a device for attaching brushes and the like to a stake, the combination of a clamp, spiral springs sunk in 85 recesses in the sides of the stake actuating said clamp, claws projecting over the front end of the stake, fixed in position against the stake by means of a washer and screw, an oblique surface on the end of the stake resting firmly on the top of the brush, said brush being fixed between the clamp claws, and oblique surface, points projecting from the oblique surface adapted to prevent the brush from slipping, a pin passing through the stake, a lever pivoted on the ends of said pin at each side of the stake, and a part jointed on the shorter arms of said lever and bent round the clamp adapted to pull back the clamp against 90 the action of the spring when the lever is worked, substantially as set forth.

In testimony whereof I have hereunto signed my name this 2nd day of October 1906, in the presence of two subscribing witnesses.

PAUL LIESKAR.
